UNITED STATES PATENT OFFICE.

WALTER S. MILLER, OF ST. LOUIS, MISSOURI, ASSIGNOR TO ST. LOUIS CAR COMPANY, OF ST. LOUIS, MISSOURI, A CORPORATION.

DRAFT-RIGGING.

No. 926,279.

Specification of Letters Patent. Patented June 29, 1909.

Application filed October 5, 1908. Serial No. 456,298.

To all whom it may concern:

Be it known that I, WALTER S. MILLER, a citizen of the United States of America, residing at the city of St. Louis, in the State of Missouri, have invented certain new and useful Improvements in Draft - Riggings, of which the following is a full, clear, and exact description, reference being had to the accompanying drawings, forming part of this specification.

My invention relates to a draft rigging for use upon railway cars, the invention having for its object the construction of a draft rigging of the character named in which the draw bar is so supported as to be capable of an easy movement in an arc of a circle when a car equipped with the rigging and connected to another car is rounding a curve in a railway track.

Figure I is a top or plan view of my draft rigging applied to the center sills of a railway car. Fig. II is a side elevation of the rigging. Fig. III is an enlarged view showing the draw bar and the draw bar stirrup in plan and the tracks on which said stirrup operates in horizontal section. Fig. IV is in part an enlarged side elevation of the draw bar and in part an enlarged vertical longitudinal section taken through the draw bar stirrup and the track rails on which said stirrup operates. Fig. V is a vertical cross section taken on irregular line V—V, Fig. IV.

In the accompanying drawings: A designates the center sills of a railway car and B a draw bar that may be of any common construction.

1 designates a pivot block that is secured to the center sills and to which the rear end of the draw bar is connected by a pivot pin 2. The forward end of the draw bar, including the coupler head and its shank B', is free of positive connection to the center sills or other parts of the car underframe and is therefore susceptible of movement in an arc of a circle in order that the coupler head may travel laterally relative to a longitudinal line through the center of a car to which my draft rigging is applied.

3 designates segment shaped track rails that are secured to the center sills A at their

lower sides and which extend laterally from said center sills. These rails are of Z-shape in cross section to provide for their attachment to the center sills and to furnish runways 4 that are located beneath the center sills and are sufficiently separated from each other to provide a passageway between them.

5 is a draw bar carry stirrup that loosely encircles the coupler head shank B' of the draw bar B and is preferably composed of sections bolted to each other in order that said stirrup may be readily fitted around the draw bar or separated therefrom without the necessity of disconnecting the parts of the draw bar. The draw bar carry stirrup is provided at its upper end with a head 6 that is adapted to travel in the passageway between the runway ledges of the track rails 3, and this head has mounted in it a bearing shaft 7 that projects beyond the sides of the head.

8 are rollers fitted to the shaft 7 and adapted to travel upon the runway ledges of the track rail 3.

The draw bar carry stirrup 5 and rollers 8 applied thereto serve as supports for the forward portion of the draw bar B during the use of said draw bar and it will be apparent that upon the occurrence of any lateral movement of said draw bar in either direction the rollers 8 will lie freely upon the runway ledges of the track rail 3 for the purpose of minimizing the friction between the members by which the draw bar is upheld.

It is desirable to maintain the draw bar of my draft rigging in a permanent position and to prevent lateral movement thereof during the shipment of a car to which the rigging has been applied, and to provide for the draw bar being so held, I attach to one of the track rails 3 of the rigging a restraining stirrup 9. This restraining stirrup embraces the coupler head shank of the draw bar and is connected to the track rail 3 to which it is applied by a pin or bolt 10 that passes through lugs 3^a projecting from said rail. When the car equipped with the draft rigging is to be placed in service, the pin 10 may be readily withdrawn and the restraining stirrup disconnected from the track rail 3 to which it is fitted, thereby freeing the

draw bar for the movement desired when it is in service.

I claim:

In a draft rigging, a draw bar, a pivotal support for one end of said drawbar, a track from which the free end of the drawbar is suspended, and a restraining stirrup detach-

ably connected to said track and embracing said drawbar, holding it from movement when the drawbar is not in use.

WALTER S. MILLER.

In presence of—

EDWARD H. GORSE,
A. DICKMANN.
